UNITED STATES PATENT OFFICE.

ANDREW A. KRAMER, OF KANSAS CITY, KANSAS.

SILO.

1,100,081.

Specification of Letters Patent. Patented June 16, 1914.

Application filed April 23, 1912. Serial No. 692,710.

To all whom it may concern:

Be it known that I, ANDREW A. KRAMER, a citizen of the United States, residing at Kansas City, in the county of Wyandotte 5 and State of Kansas, have invented certain new and useful Improvements in Silos; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to silos, and more particularly to a silo constructed of sheet metal, the principal object of the invention being to provide a structure of this character which may be erected at a reasonable 20 initial cost and will be more permanent and satisfactory than structures of this kind composed of wood or concrete. In accomplishing this object, I have provided the improved details of structure hereinafter described and illustrated in the accompanying 25 drawings, wherein:—

Figure I is a side elevation of a silo constructed according to my invention, showing a door opening partly closed. Fig. II is an enlarged sectional view of the concrete base and part of the metal shell. Fig. III is a perspective view of the base flange with one of the shell plates in position, showing the preferred method of starting 35 the erection of the plates. Fig. IV is an enlarged perspective view of one of the plates. Fig. V is a similar view of superimposed plates showing the method of mounting upper and lower plates. Fig. VI is a perspective view of the cap frame. Fig. VII is an inside perspective view of 40 part of the door frame and one of the doors, a section of the door being broken away to show the gasket. Fig. VIII is a horizontal 45 section of part of the shell, showing the door-frame and door in horizontal section, on the line VIII—VIII, Fig. VII. Fig. IX is an enlarged horizontal section of one of the door jambs, showing the connection of 50 the shell and the tightening bolt. Fig. X is a front view of the door, showing the fastener.

Referring more in detail to the parts:— 1 designates the base of the silo, which is

constructed of concrete and has a circumferential groove 2 in the top for receiving the base of the shell. Seated in the groove 2 is a circular angle iron 3 which is held in place by angle hooks 4 that are embedded in the concrete base while the latter is being 50 formed. The angle member 3 extends entirely around the base but is cut at a door position to provide recesses 5.

Seated on the angle member 3 is the first tier of shell plates 6, the ends of which are 65 riveted together to form a solid collar except for a door opening 7, which rises from the base above the angle slots 5, the plates 6 having their ends terminating at the door position, and being provided with lips 8 70 which extend back into the body of the structure to form the door jambs. On the upper edge of each of plates 6 is an in-turned shoulder 9 having an upturned flange 10 forming a seat and back for the 75 lower edge of a shell plate in an upper tier. The plates in the upper tier are seated on the shoulders 9 of the plates in the lower tier and riveted to the back flange 10 to form an integral structure. I prefer to 80 place fiber or like packing 11 between the lower edges of the plates in the upper tier and the back flanges 10 of the plates in the lower tier and between the overlapping ends of the plates in the same tier in order to 85 assist in making the structure air and moisture proof. Succeeding tiers are formed in the same way until the silo has been erected to a desired height.

After the shell plates have been erected, 90 the door-frame is applied thereto, such frame consisting of angle members and spacers which are arranged and combined in the following manner: At the inside of the structure an angle iron 12 is raised against 95 each of the jamb flanges 8 of the angle plates and seated in the groove formed by the flange and body of the plate. An angle bar 13 is then raised against the outer face of said jamb plate and fitted over the angle 100 formed by the flange 8 and outer face of the shell plate to bind the flanges and adjacent portion of the plates between same and inner bar 12. Prior to the erection of the shell and jamb members, these parts have had bolt 105 holes 14 formed in the angles thereof so that when the parts are assembled, as described, bolts 15 may be projected through the holes

so that the bolt heads 16 will nest in the groove of the inner angle iron. Washers 17 are then fitted over the corner of the outer angle iron and nuts 18 applied to the threaded shanks of the bolts and tightened against the heads of the V-shaped washer to tighten the parts snugly together.

When both of the door jambs have been erected, cross-bars 19 may be inserted to space the jambs apart, said cross-bars being spaced at regular intervals throughout the height of the door opening in order to coöperate with the door members. I also prefer to fasten the metal strips 20 to the outer angles of the door-jambs and to the shell plates in front of the cross-bars 19 to give the structure rigidity and provide means for fastening the bars 19 in place.

20 21 designates the top of the silo, which may be of any suitable construction, but preferably provided with a manhole 22 through which ensilage may be delivered to the interior of the silo.

25 As it is important to keep moisture out of the silo, a door especially adapted for tightly closing the door opening is provided. This door preferably comprises hinge members 23 which are fixed to one of the inner door

30 jamb members and comprise cylindrical members 24 which are projected into the shell structure past the inner edges of the jambs, the hinge members being arranged in pairs at each door position. A door 25 is provided for each door position on the frame and adapted to fit snugly against the inner edges of the jambs. The doors are preferably formed of wooden strips arranged horizontally and having tongue and groove connection, and hung by hinge members 26 having straps 27 extending over the edge thereof and provided with elongated pin slots 28, the edges of the straps being bent back to

35 abut against the part of the strap body which lies against the edge of the door. A rod 29 extends through the elongated strap slots 28 and through the cylindrical members 24 of the frame hinge members 23, the upper end of the rod being turned laterally

40 to form a hook that will keep the same in place and prevent its falling through the hinges. It is apparent that with a hinge of this kind the door may pivot on its hinge and may also move toward and from the door opening, so that as the ensilage settles in the silo the pressure will tend to force the doors into close contact with the jambs.

In order to make the door opening moisture and air proof, I prefer to line the jambs and cross-bars 19 with strips 30 of suitable packing which will insure the moisture and air proofing of the door connection.

While the contents of the silo will tend to force the door to a tight closure, fresh ensilage will not pack sufficiently to insure

the proper closing and of course the door would not be held in place after the ensilage is removed. In order to close the door from without, I provide a fastening comprising a double-handed lever 31 which is pivotally mounted at its center on a pin 32 that is carried on a vertical cleat 33 on the front of the door.

Pivottally connected with an intermediate bar 34 of the lever at each end thereof is a pressure bar 35 which extends through a bracket 36 on a cleat 37 on the side of the door, and has a beveled inner face 38 adapted for projection from the outer face of the adjacent door-jamb, the beveled under face 39 being adapted for pulling the door outwardly as the bars are set, to cause the outer face of the door to bind tightly against the inner edges of the jambs. I also provide ladder rungs 39 on the outer faces of the doors whereby a person may climb to the top of the doors when the opening is closed. It is apparent that after the shell is erected, the doors may be installed as they are needed, and that when the ensilage is removed from the top the doors may be taken down to keep the upper door level on a level with the top of the ensilage so that ready access to the latter is afforded.

It has been found that with a sheet metal structure like the one herein described the common disadvantage of the expansion and contraction of the shell, due to changes in temperatures, is obviated so that it is unnecessary to tighten and loosen hoops, or the like, which, with silos constructed of other material, must be constantly cared for, in order to keep the shell from bursting when the ensilage swells or from separating or falling apart when the silo is empty and the shell dried by summer heat.

It has also been found that by painting the interior of the shell with a preparation prepared for that purpose, the shell is protected from acids or moisture of the ensilage so that there is little tendency of the shell to disintegrate and the not uncommon tendency of the ensilage to hold on account of contacting a moist shell is obviated.

Having thus described my invention, what I claim as new therein and desire to secure by Letters-Patent is:-

1. A silo comprising a shell formed of sheet metal and having a vertical opening therein, the sheet metal having flanges turned inwardly at the sides of the opening, door jambs connected with said flanges, said jambs comprising inner and outer angle irons, having their flanges lying against the angle portions of the sheet metal and means for securing said door jambs to said shell.

2. A silo comprising a shell formed of sheet metal and having a vertical opening therein, the sheet metal having flanges turned inwardly at the sides of the opening,

door jambs connected with said flanges, said jambs comprising inner and outer angle irons, having their flanges lying against the angle portions of the sheet metal, and bolts extending through the vertices of the angles of the shell and the angle irons to bind the parts together.

In testimony whereof I affix my signature in presence of two witnesses.

ANDREW A KRAMER.
